COMBINED SACKING AND WEIGHING MACHINE

James L. Roach and William F. Roach, Plainfield, and
William H. Pape, Waverly, Iowa, assignors to J. Roach
Sons, Inc., Plainfield, Iowa, a corporation of Iowa

Filed May 29, 1963, Ser. No. 75,119

Term of patent 14 years

(Cl. D55—1)

FIG. 1

FIG. 6

FIG. 2

FIG. 5FIG. 4 FIG. 3FIG. 1 is a side elevational view of a combined sacking and weighing machine showing our new design,

FIG. 2 is an elevational view of the side opposite that shown in FIG. 1,

FIG. 3 is an end elevational view thereof,

FIG. 4 is an elevational view of the end opposite that shown in FIG. 3,

FIG. 5 is a top plan view thereof, and

FIG. 6 is a bottom plan view thereof.

The dominant features of my design reside in the portions shown in full lines.

We claim:

The ornamental design for a combined sacking and weighing machine, as shown and described.
